MANUFACTURE OF SHOES

Original Filed Sept. 26, 1930

UNITED STATES PATENT OFFICE

JACOB S. KAMBORIAN, OF WEST NEWTON, MASSACHUSETTS, ASSIGNOR TO NORTHERN MACHINE CO., INC., OF BOSTON, MASSACHUSETTS, A CORPORATION OF MASSACHUSETTS

MANUFACTURE OF SHOES

Original application filed September 26, 1930, Serial No. 484,553. Divided and this application filed August 11, 1931. Serial No. 556,375.

My present invention relates to an improvement in the manufacture of shoes and more particularly to a process for treating the bottoms of shoes, which is applicable to 5 McKay shoes, more especially to McKay shoes when made by a cementing process and without the use of tacks, although it is also applicable to Welt shoes. When manufacturing shoes by a cementing process, where tacks are not used, and particularly at the toe portion, the shoe is placed in a bed lasting machine and the toe portions of the upper materials are wiped over by the lasting wipers. Even 10 though the wiping operation be repeated several times, the upper materials have a tendency to assume their normal position as often as the wipers are withdrawn, so that the usual cement does not have time 15 to set and hold the material flat and smooth. Moreover, the lasting wipers themselves are not adapted to exert pressure in such a way as effectively to level or smooth the upper materials at this point, with the result that 20 when the outsole is applied, there will be lumps or ridges between the outsole and insole at the toe portion of the shoe, unless that portion of the shoe bottom is subsequently ironed, which entails a separate operation after removal from the lasting machine. I am aware that it has been proposed to cement the edge of the upper to 25 the inner sole and to hold it while the cement is setting by devices having insole 30 penetrating prongs, nails or the like, but all such proposals so far as known to me have proven ineffective and of no commercial value by reason of the difficulty of applying such holding devices and especially the difficulty of removing them at the completion 35 of the operation, such devices causing injury to the shoe parts and in some instances necessitating the employment of lasts of special form, while devices designed to exert pressure upon the entire shoe bottom, for example, in cementing an outer sole in 40 place, are not adapted to exert the intense localized pressure necessary to level and flatten the wiped-in upper material at the 45 toe.

The principal object of the present invention is to eliminate and obviate the difficulties above mentioned, and to provide a method or process whereby the toe portions of the upper materials, after being wiped in by the shoe lasting wipers, may be levelled and flattened and reliably held in such condition until the retaining cement has set by means which does not injure the last or shoe parts and which can be easily applied and released. 55

Such process may be carried out for example by the employment of a device which will exert sufficient local pressure upon the folded-in upper materials to level or smooth the same so as to eliminate wrinkles, corrugations or the like, such for example, as shown and described in my copending application, Serial No. 484,553, filed September 26, 1930, of which this application is 60 a division, but is manifestly capable of being carried out by other means. 65

The process may be understood by reference to the accompanying drawing, in which: 70

Fig. 1 is a side elevation of one device useful in the practice of the invention, said device being shown in position to carry out the final step of the process; 75

Fig. 2 is a plan view partly in section on the line 2—2 of Fig. 1;

Fig. 3 is a sectional view on the line 3—3 of Fig. 1;

Fig. 4 is a cross-sectional view on the line 4—4 of Fig. 1; 80

Fig. 5 is a bottom plan view of the clamping plate forming an essential element of the device; and

Fig. 6 is a cross-sectional view on the line 6—6 of Fig. 5. 85

Referring now to the drawing, the device illustrated therein comprises an arm 1 having at one end thereof a cup-shaped member or cap 2 pivoted at 3 and adapted to fit over the peak 4 of the forepart of a last 90 5. The opposite end of the arm 1 is bent to form an offset arm 6 having therein a longitudinal slot 7, said two arms being in the shape of an L. Cooperating with the arm 6 is a bracket 8 dovetailing with said 95 100

arm for guidance, as clearly illustrated in Fig. 4. A bolt 9 extends through the bracket 8, having a squared portion 10 to prevent rotation, and having a threaded stem 11 extending through the arm 6. A wing nut 12 is provided to clamp the arm 6 and bracket 8 in adjusted position, a washer 13 being interposed between the wing nut 12 and arm 6. The bracket 8 is angled to form an extension 14 having a threaded boss 15 at its outer end. Through this threaded boss is adapted to be screwed a threaded stem 16 having a handle 17 on its upper end and a rounded knob 18 on its lower end. This rounded end 18 is adapted to seat in a recess or depression 19 in a rivet 20, this rivet 20 uniting the two sections 21 forming the clamping or levelling plate. This plate is preferably fairly thin, but is sufficiently stiff and rigid to enable it to transmit the necessary intense localized pressure to the folded-in toe material without yielding or buckling, and is of such size and contour as to confine the compressive action to the toe portion 25 of the shoe, it being noted that this plate is of such width, inwardly of its outer lateral margin, as substantially to cover the entire width of the folded-in upper material exposed by retraction on the lasting wipers, 30 and is thus capable of exerting flattening or leveling pressure over substantially the entire area of the folded-in material, and particularly along the margin of the shoe bottom, while the cement is setting. The under 35 surfaces of these sections 21 are smooth, in the sense that they have no prongs, points, or projections such as would penetrate the material of the shoe for holding engagement therewith, but in thus describing them as 40 smooth I do not exclude such knurling or similar treatment as illustrated at 22, to insure a gripping thereof on the edges 23 of the upper materials 24. A spring 25 is provided having a bearing in each of the sections 21 and normally tending to hold said parts in separated position.

The process to which this application is directed will not be described with particular reference to the device illustrated in the drawing but it will be understood that I am not limited thereto and that other means can be employed to carry out the process. The insole 26 and upper materials 24 are first assembled on the last 5 in the usual manner, 50 while the last is in a bed-lasting machine (not shown). The edges 23 of the upper material are pulled over at the toe and the sides lasted. Adhesive is inserted between the edges 23 and insole 26, and the lasting 55 wipers 27 are operated to pull over and wipe the edges 23 at the toe part.

The wipers 27 are then separated and/or lifted a sufficient distance to allow the application of the smoothing and levelling plate 60 21 to the toe of the shoe bottom, as illus-

trated in dotted lines in Fig. 1. Then, as a convenient means for applying pressure to the plate 21, the cap 2 is fitted over the peak of the last and the arm 1 swung until the knob 18 can be seated in the depression 19 in the rivet 20. Thereupon the parts will be in the position illustrated in dotted lines in Fig. 1.

Thereafter, on rotation of the handle 17, the stem 16 will be threaded downwardly 75 through the boss 15, exerting pressure on the plate 21. This pressure will tend to move the stem 16 and hence the plate 21 toward the heel of the shoe, the clamping action being stopped when the plate 21 has reached a position approximately as illustrated in full lines in Fig. 1.

This clamping and moving action will not only complete the pulling over action, but will also smooth out, level and press the edges 23 of the upper materials at this toe portion.

As the plate sections 21 are moved toward the heel, they may expand, the spring 25 tending to force said sections outwardly, 80 so as to insure perfect action on the edges 23.

The device is left in clamping position for a predetermined length of time sufficient to permit the cement to set, and is then removed, at which time the cement will have set and the upper materials are securely held in permanent position, ready for the application of the outsole. Preferably a quick setting cement will be used, either one which is applied hot and which sets upon cooling, or one comprising a highly volatile solvent which sets by evaporation of the solvent.

The above description makes it readily apparent to one skilled in the art that my new and novel process in its preferred form may be briefly described as comprising the following steps in whole or in part and in any appropriate order:—

1. Assembling the insole and upper materials upon a last and mounting them in a lasting machine, the last being of standard construction, that is to say requiring no special preparation for this particular use.

2. Pulling over the edges of the upper materials.

3. Rendering the material adhesive.

4. Operating the lasting wipers.

5. Withdrawing the lasting wipers from operative position.

6. Exerting pressure upon the folded upper material and the toe portion in such a way as to level and smooth such material.

7. Maintaining the pressure until the adhesive is set.

It will of course be understood that since certain of the above steps are old and well known, the novelty of this invention resides in the steps which are new per se, and in

the combination of such steps with one or more of the old steps as will appear from a consideration of the following claims wherein the spirit and scope of the invention are set forth.

I claim:

1. That process of making shoes which comprises as steps assembling an upper and an imperforate insole upon a last, wiping in the margin of the upper at the toe by means of lasting machine wipers, retracting the wipers, interposing adhesive between the wiped-in portion of the upper and the opposed surface of the insole, applying flattening pressure, while the shoe is in the lasting machine, locally to substantially the entire mass of the wiped-in toe material by means movable relatively to the lasting wipers while leaving the shoe bottom exposed rearwardly of its toe portion, maintaining such flattening pressure, without penetration of the insole by pressure maintaining parts, for a time sufficient to permit the adhesive to set, and removing the shoes from the lasting machine to make room for another, while still maintaining such pressure.

2. That improvement in methods of making shoes which consists in working the margin of the toe end portion of a shoe upper into lasted position upon the bottom face of an insole mounted on a standard last, applying pressure to said margin at the toe portion only of the shoe while leaving the bottom of the shoe exposed rearwardly of said toe portion and by the use of cementitious material causing such toe material to adhere to the insole, maintaining pressure against such marginal toe material to flatten and level the latter by the application of force reactive between said material and the cone portion of the last, until the cementitious material has substantially set and while lasting the heel end of the shoe, thereafter releasing the margin from such pressure, applying an outsole, and securing the latter to the insole.

3. That improvement in methods of making shoes which consists in working the margin of the toe end portion of upper materials into lasted position upon the bottom face of an insole on a last by means of unheated lasting machine wipers, applying a presser member, independent of the wiper, to said wiped-in margin, said presser member contacting with such wiped-in material from the inner edge of the latter outwardly substantially as far as the edge of the insole, clamping said presser member against such margin with a force sufficient to flatten and level all of said marginal wiped-in toe material, maintaining such pressure, without penetration of the insole by pressure-maintaining parts, until the marginal material has set, and removing the shoe from the last-

ing machine before such material has completely set to make room for another shoe.

4. That improvement in methods of making shoes of that kind in which the marginal portion of the upper lies substantially flat in contact with the inner surface of the inner sole, which comprises as steps working the marginal portion of the upper at the toe of the shoe inwardly over the bottom of the insole, thereby producing folds or pleats in said marginal material where it overlies the toe of the insole, causing the opposed surfaces of the insole and such folded-in marginal material to become adhesive, and exerting compressive force, having a component in a direction substantially perpendicular to the bottom face of the insole, upon substantially all of said pleated toe material throughout substantially its entire width, the pressure being confined to the toe portion of the shoe and being of sufficient intensity and so applied as to flatten and level the pleated material, whereby to produce a surface appropriate for the application of an outer sole without recourse to pounding, lasting the heel end of the shoe while maintaining such pressure, without penetration of the insole by pressure-applying or pressure-maintaining elements, releasing the pressure, and applying an outer sole.

5. That improvement in methods of making shoes which consists in lasting the margin of upper materials about the toe end of a last inwardly over the bottom face of an insole on the last, then disposing a substantially rigid imperforate clamping member upon the wiped-in upper materials, said clamping member being of a size and contour such as to contact with and substantially cover all of such wiped-in toe material while leaving the bottom of the shoe uncovered rearwardly of its toe portion, applying pressure to the clamping member, in such a way as to avoid penetration of the insole by force-applying or maintaining parts, while exerting sufficient force between the last and clamping member to flatten substantially all of the wiped-in toe materials against the insole, and maintaining the pressure thus applied until the margin of the upper materials has substantially set in lasted position and while lasting the heel end of the shoe.

6. That improvement in methods of making shoes which comprises working the margin of the end portion of the upper materials into lasted position over the bottom of an insole mounted on a last by the use of lasting machine wipers, withdrawing the wipers from their advanced position and, while the shoe is still in the lasting machine, disposing upon the wiped-in margin of the upper materials a plate devoid of work-penetrating elements, the entire under surface of said plate being substantially in the same plane,

the plate being of such size and contour as substantially to cover all of the wiped-in material while leaving the bottom of the shoe uncovered except adjacent to said end portion, clamping said plate against the wiped-in material with pressure sufficient to press said material substantially flat against the bottom face of the insole, maintaining the clamping pressure thus applied, without penetration of the insole by clamping members, until the upper materials have substantially set in lasted position, and removing the shoe from the lasting machine with the plate still clamped in position before the material has completely set so as to make room for another shoe.

7. That improvement in methods of making shoes which consists in lasting the margin of upper materials about an end of a last inwardly over the bottom face of an insole on the last by means of unheated lasting machine wipers, retracting the wipers, then disposing a substantially rigid pressure-applying member, independent of the wipers, upon the lasted-in margin of the upper materials at the toe, said member having a substantially plane under surface of such size and contour as substantially to cover all of such wiped-in toe material while leaving the bottom of the shoe uncovered rearwardly of its toe portion, pressing said member against the wiped-in toe materials with pressure sufficient to flatten and level substantially all of said materials against the bottom face of the insole, holding said member in pressure-applying relation to such wiped-in material without penetration of the insole by pressure-maintaining parts until such material is substantially set in lasted position, and, while so holding the parts and before the material has completely set, removing the shoe from the lasting machine to make room for another.

8. That process of making shoes which comprises as steps assembling an upper and an insole upon a last, disposing the last and assembled material in a lasting machine having lasting wipers, wiping-in the toe portion of the margin of the upper by means of the lasting wipers, removing the wipers from upper engaging position, applying adhesive to the wiped-in material, disposing a presser member, separate from the lasting wipers, upon the wiped-in material at the toe portion of the shoe, said presser member being of such size and contour as to engage and cover substantially all of such wiped-in toe material while leaving the bottom of the shoe exposed rearwardly of the toe portion to permit operations upon said rearward part, applying pressure to said presser member sufficient to flatten and level the wiped-in toe material, and maintaining said presser member in pressure-applying position, until the adhesive has set, without penetration of

the insole by pressure-maintaining parts, and while so maintaining the pressure, removing the shoe from the lasting machine to make room for another.

9. That process of making shoes which comprises as steps assembling an upper and an insole upon a last, disposing the last and assembled material in a lasting machine having lasting wipers, wiping-in an end portion of the margin of the upper by means of the lasting wipers, removing the wipers from upper engaging position, interposing adhesive between the opposed surfaces of the wiped-in material and the insole, disposing a substantially rigid presser member in contact with that portion of the wiped-in material at the end of the shoe which has been folded over the insole by the wipers, said presser member being of such size and contour as substantially to cover all of such wiped-in material at the end of the shoe while leaving the bottom of the shoe uncovered except at said end portion, applying localized pressure by means of said presser member sufficient to flatten and level the wiped-in material at the end of the shoe, and maintaining such pressure without penetrating or engaging the insole by pressure-maintaining parts until the adhesive has set and while lasting the other end of the shoe.

10. That process of making shoes which comprises as steps assembling an upper and an insole upon a last, folding the margin of the toe portion of the upper inwardly over the edge of the insole, causing said folded-over portion of the upper and the opposed surfaces of the insole to become mutually adhesive, placing a substantially rigid presser element devoid of work-penetrating parts upon said folded-over toe material, said element being of such size and contour as to contact with substantially all of such wiped-in toe material while leaving the bottom of the shoe uncovered rearwardly of the toe portion, causing said element to press such material with sufficient pressure to flatten and level it, and maintaining said element under flattening pressure without penetration of the insole by pressure-maintaining parts until the adhesive has set and while lasting the heel end of the shoe.

11. That process of making shoes which comprises as steps assembling an upper and an imperforate insole upon a last, wiping-in the margin of the upper at the toe by means of lasting machine wipers, interposing a quick setting cement between the wiped-in material of the upper and the opposed surface of the insole, disposing a rigid presser element having a substantially flat work engaging surface in contact with the wiped-in material at the toe portion of the shoe bottom while the shoe is still in the lasting machine, said presser element being of such size and contour as to engage substantially

all of such wiped-in toe material, applying sufficient pressure to said presser element to flatten and level the wiped-in toe material, and maintaining said element under such flattening pressure without perforation of the insole by pressure-maintaining parts and during removal of the shoe from the lasting machine to make room for another shoe.

12. That process of making shoes which

10 comprises as steps assembling an imperforate insole and an upper upon a last of standard construction, pulling over the margin of the upper at the toe portion, introducing adhesive between the opposed 15 surfaces of the insole and upper at the toe portion, wiping in the margin of the upper over the forepart of the insole by means of lasting machine wipers, retracting the wipers, applying a levelling plate independent of the wipers to the wiped-in toe material while the shoe is still in the lasting machine, said plate being of such size and contour as to engage substantially all 20 of such wiped-in toe material while leaving the bottom of the shoe uncovered rearwardly of the toe portion, pressing the leveling plate down upon said wiped-in toe material, maintaining pressure upon said plate sufficient to flatten and level the wiped-in toe 25 material until the adhesive has set but without penetration of the insole by pressure-maintaining parts, and lasting the heel end of the shoe while maintaining such pressure.

13. That improvement in methods of mak-

25 ing a lasted shoe devoid of metallic fasteners at its toe and having its bottom surface at the toe substantially flat and level, which comprises as steps assembling an upper and an imperforate insole upon a last, wiping-in 30 the toe portion of the upper by means of the wipers of a bed lasting machine, retracting the wipers, disposing a substantially rigid imperforate presser plate upon the wiped-in material, the plate being of such 35 size and contour as to engage substantially all of such wiped-in toe material while leaving the bottom of the shoe uncovered rearwardly of its toe portion, applying sufficient local pressure to the plate to flatten and 40 level the wiped-in toe material, and maintaining such pressure upon the plate during the lasting of the heel end of the shoe and until the wiped-in toe material has set in level condition but without penetration or 45 perforation of the insole by pressure-maintaining parts.

14. That process of making shoes which comprises as steps assembling an upper and insole upon a last, disposing the last and 50 assembled material in a lasting machine having lasting wipers, wiping-in the toe portion of the margin of the upper by means of the lasting wipers, moving the wipers from their advanced wiping position, causing the 55 inner surface of the wiped-in material to

become adhesive, disposing a rigid presser member, separate from the lasting wipers and devoid of projecting prongs, upon the wiped-in material uncovered by movement of the wipers from their advanced position so as to engage and cover substantially all of such wiped-in toe material and while leaving the bottom of the shoe uncovered rearwardly of its toe portion, and, while the shoe is still in the lasting machine, applying pressure to said member substantially at the center of width thereof and sufficient to level and flatten the wiped-in toe material so as to make the shoe bottom ready for application of an outer sole, and, while lasting the heel end of the shoe, maintaining such pressure at the same point on said member until the adhesive has set but without penetration of the insole by pressure-maintaining parts.

15. That improvement in methods of making shoes which comprises wiping-in the margin of the toe portion of the upper materials over the bottom face of an insole on a last by means of the wipers of a lasting machine thereby forming pleats in such marginal material, retracting the wipers, applying in continuous engagement with the margin of the upper materials, uncovered by retraction of the wipers around the toe, a substantially U-shaped inflexible presser member devoid of work-penetrating parts and extending from the inner edge of the wiped-in material outward as far as the edge of the insole, said presser member leaving the bottom of the shoe uncovered rearwardly of its toe portion, forcibly urging said presser member toward the bottom face of the insole whereby to flatten the pleated wiped-in material at the toe sufficiently to produce a level surface without recourse to grinding or pounding, and maintaining said presser member in compressive relation to said wiped-in material, without perforation of the insole by pressure-maintaining devices, until such material has set in flat and level condition and while lasting the heel end of the shoe.

16. That improvement in methods of making shoes which comprises lasting the margin of upper materials about the toe end of a last inwardly over the bottom face of an insole on the last by the use of wipers in a lasting machine, retracting said wipers, applying a rigid clamping plate devoid of penetrating prongs in substantially continuous engagement with the pleated wiped-in marginal material at the toe end of the shoe, such plate being of such size and contour as to engage and cover substantially all of such wiped-in toe material while leaving the bottom of the shoe uncovered rearwardly of its toe portion and while the shoe is still in the lasting machine, causing said clamping plate to press substantially all of the wiped-

in upper material forcibly against the bottom face of the insole with pressure sufficient to flatten said pleated material from a location substantially over the edge of the insole inwardly to the inner edge of said material, removing the shoe from the lasting machine, and holding said clamping plate in pressure-applying position, while avoiding penetration of the insole by pressure-maintaining parts, until the margin of the upper materials has substantially set in lasted position.

17. That method of manufacturing shoes which includes the following steps: assembling the insole and upper upon a last, mounting the last in a lasting machine, folding over the edge of the upper at the toe portion, rendering such edge adhesive, operating lasting wipers to bring the edge of the upper into contact with the insole, withdrawing the wipers from the operating position, placing a plate upon the edge of the upper uncovered by withdrawal of the wipers, while the shoe is still in the lasting machine, applying downwardly exerted pressure upon said plate at such an angle that the plate moves rearwardly, causing the plate to expand laterally as it moves along the shoe bottom to a final position, and maintaining such downwardly exerted pressure upon the plate in said final position until the adhesive has set.

18. That process of manufacturing shoes which includes the following steps: assembling the insole and upper upon a last, mounting the last in a bed lasting machine, folding over the edge of the upper at the toe portion, rendering such edge adhesive, operating the lasting wipers to bring the edge of the upper in contact with the insole, withdrawing the wipers from operating position, applying pressure means to the edge of the upper uncovered by withdrawal of the wipers while the shoe is still in the lasting machine, exerting pressure upon such means downwardly toward the insole while caus-

ing said pressure means to move rearwardly, and maintaining the edge of the upper under such downwardly exerted pressure until the adhesive has set.

19. That process of making shoes which comprises as steps assembling an upper and an insole upon a standard last, wiping in the margin of the upper at the toe by means of lasting machine wipers, retracting the wipers, causing the wiped-in material and the opposed surfaces of the insole to become mutually adhesive, disposing a substantially flat U-shaped plate, independent of the wipers, upon the wiped-in toe material, said plate covering the wiped-in material from the outer edge of the shoe bottom inwardly substantially to the edge of said upper material, applying pressure to said plate sufficient to flatten said wiped-in toe material while exerting upon said plate a component of force longitudinally of the shoe bottom, and maintaining the flattening pressure upon said wiped-in material until the adhesive has set.

20. That improvement in methods of making a lasted shoe devoid of metallic fasteners at its toe and having its bottom surface at the toe substantially flat and level without recourse to pounding, which comprises as steps, assembling an upper and an inperforate insole upon a standard last, wiping in the margin of the upper at the toe by means of lasting machine wipers, retracting the wipers, disposing a presser plate, independent of the wipers, upon said wiped-in toe material, applying pressure to said plate in such a way as to urge it longitudinally of the insole until a substantial degree of pressure has been attained thereby to complete the pulling over operation, and thereafter maintaining pressure upon said plate in a direction toward the shoe bottom sufficient to level said wiped-in material and hold it flat until it has set in level condition.

JACOB S. KAMBORIAN.
